United States Patent Office

Des. 200,288
Patented Feb. 16, 1965

200,288

SIGN

Robert Orion Smythe, Cedar Rapids, Iowa, assignor to American Dairy Queen Corporation, Minneapolis,
Minn., a corporation of Delaware

Filed Oct. 21, 1963, Ser. No. 77,064

Term of patent 14 years

(Cl. D1—12)

FIG. 1 is a front perspective view of a sign embodying my new design;

FIG. 2 is a side elevational view taken from the left of FIG. 1;

FIG. 3 is a side elevational view taken from the right of FIG. 1;

FIG. 4 is a front elevational view thereof, the rear being a mirror image of the front shown; and

FIG. 5 is a top plan view thereof.

I claim:

The ornamental design for a sign, as shown and described.
